(57) **CLAIM**

I claim the ornamental design for a zipper pull, as shown and described.

DESCRIPTION

FIG. 1 is a perspective view of a zipper pull showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view thereof taken along line 8-8 shown in FIG. 6; and,

FIG. 9 is a perspective view of the zipper pull illustrating my new design in the environment of a handbag.

Broken lines are used to illustrate environment and unclaimed portions of the zipper pull.

Broken lines, and any boundary created thereby, form no part of the claimed design.
